UNITED STATES PATENT OFFICE

2,533,757

SANITARY CONTAINER

Arsene Beauchemin, Montreal, Quebec, Canada

Application May 18, 1946, Serial No. 670,704

2 Claims. (Cl. 206—1)

1

This invention relates to containers and more particularly to containers for the hygienic, overnight preservation of artificial dentures.

In general, dentures are removed from the mouth at night and placed in any available container, usually a drinking glass or cup which is filled with water or an antiseptic solution. Such containers are often undistinguishable from similar household articles and may be inadvertently used for other purposes without proper sanitary precautions being taken, a practice which obviously can lead to the spreading of disease, germs, or at least unhygienic living conditions. In addition, the liquid in the container is usually colorless and it has occurred that the foul liquid has been consumed or utilized in some way, such as for brushing the teeth through inadvertence or mistake. Further, this unsanitary practice may have harmful results to the user of the dentures as they are left for relatively long periods with the liquid exposed to dust and other air-borne foreign matter which may contaminate the liquid thus the dentures therein.

In brief the present invention contemplates a distinctive container having a peripheral lip which is unsuitable for pouring liquids or drinking therefrom and which is provided with a seating for proper disposition of the dentures therein, and additionally provided with a protective cover.

In accordance with the invention, one object is to provide a container which even under casual observation will be seen to be provided for a distinct purpose unrelated to normal household usage. Another object is to provide a container which renders difficult and discourages the act of drinking therefrom particularly by small children who fail to perceive the unsanitary condition of the container. Still other objects thereof are provision for the proper disposition of the dentures or partial dental restorations in the container to the end that they are not subjected to stresses of any kind which may distort or fracture the denture, and to facilitate the insertion or removal of the dentures therefrom.

In considering the invention in greater detail, reference will be made to the attached drawings in which:

Figure 1 is a perspective view of one embodiment of the invention.

Figure 2 is a similar view thereof in which the cover has been removed.

Figure 3 is a top plan view thereof.

2

Figure 4 is a vertical sectional view along the line 4—4 of Figure 3.

Figure 5 is a vertical sectional view along the line 5—5 of Figure 3.

5 Figure 6 is a perspective view of a modified form of the invention.

Figure 7 is a transverse vertical sectional view of Figure 6.

10 Figure 8 is a plan view, with the cover removed, of still another form of the invention.

Figure 9 is a vertical sectional view along the line 9—9 of Figure 8, and through the attached cover.

15 Referring more in detail to the drawings in which similar reference characters designate corresponding parts, throughout the several views it will be seen that the invention, as disclosed in Figures 1 to 5, consists of a cruciform container 10, provided with a cover 11. The cover has a marginal rib 12, to effect a relatively dust-proof seal between the container and the said cover, although it is obvious that other sealing means may be resorted to with equal effectiveness.

20 25 The bottom of one arm 13, of the cruciform container is below the level of the bottom of the remaining arm 14, and is provided with a raised, arcuate portion 15, in the center thereof. The upper denture is disposed in the arm 13, with the rib of the said denture partially supported on the raised portion 15, and the lower denture is disposed in the arm 14, at right angles to, and bridging the upper denture as shown most clearly in Figure 4. By arranging the dentures as indicated a minimum strain is imposed upon each denture and they are nested in a compact manner commensurate with the shape of the container.

30 35 The peripheral lip of the container is fluted or notched 16, and this irregular edge coupled with the fact that any portion of the edge is much more narrow than the mouth of a child, renders the act of drinking from the container exceedingly difficult, and discourages such attempts.

40 45 The container is filled with water or preferably an antiseptic solution which is displaced when the dentures are deposited therein. To avoid wastage of the antiseptic and the inconvenience an excessive amount of the liquid would cause through overflowing when the dentures are placed in the container, an indicating means 17, such as shown in Figures 1 and 2, is provided in which the numerals 1 and 2 indicate the liquid

50 55 levels for one or two dentures respectfully and

the letters A and B indicate the amount of concentrated antiseptic required for the total liquid levels 1 and 2 respectively.

In the modification shown in Figures 6 and 7, the container 20, has a cruciform inner configuration and a distinctive outer appearance which includes opposed curvilinear enlargements 21, to discourage drinking and pouring from the container and fanciful legs 22, to indicate the specific use thereof.

The container 20, is adapted for a single denture which is disposed in one arm 23. The lower center portion 24, of the said arm is restricted to maintain the denture in an upright position. The remaining arm 25, is relatively shallow and curves downward and inward to the arm 23, to the end that the thumb and finger are directed toward the denture and facilitates the insertion and removal of the said denture therefrom.

It is obvious that a cover, liquid indicating means and a crenated or fluted periphery may be employed in combination with the container described and illustrated in Figures 6 and 7.

In the form of the invention shown in Figures 8 and 9, the container is particularly adaptable to partial dental restorations although it should be understood that a complete denture may be disposed therein, in a substantially horizontal position. Exteriortly the container 30, has a shallow, circular appearance with a crenated peripheral flange 31, for the purpose hereinbefore described. The top surface of the flange is additionally provided with an annular recess 32, which coacts with the annular rib 33, of the cover 34, to effect an efficient seal for proper 30 hygienic conditions.

Interiorly the container 30, forms an arcuate basin 35, rising concentrically to form a nodule 36, which is still further elevated at its rear edge to provide a fulcrum 37, for the lever 38. To 40 the rear of the fulcrum a depression 39, permits the short arm 40, of the lever to be depressed and thus raise the three arms which follow the contour of the nodule, 36, and the bottom of the arcuate basin 35. It is obvious that the denture 45 is supported on the arms of the lever and is raised from the basin by depressing the short arm 40, all for the purpose of facilitating the removal of the denture from the container.

In general the salient features of my invention are carried into effect in all embodiments thereof and each container may be formed from plastic, glass or ceramic material which may be transparent or translucent.

What I claim is:

1. A partitionless leakproof container to support a pair of dentures in nested vertical position in an antiseptic solution, having an interior cruciform configuration, walls of a height sufficient to extend above the top portion of said dentures when in vertical position, in which one arm is less shallow than the remaining arm, a raised arcuate portion formed at the center of the bottom of said first arm to support a denture in vertical position, a crenated peripheral lip and a cover for the container.

15 2. A partitionless leakproof container to support a pair of dentures in nested vertical position in an antiseptic solution, having an exterior irregular substantially cruciform configuration, an interior cruciform configuration, walls of a height sufficient to extend above the top portion of said dentures when in vertical position, in which one arm is less shallow than the remaining arm, a raised arcuate portion formed at the center of the bottom of said first arm to support a denture in vertical position, a crenated peripheral lip and a cover for the container.

20 25 ARSENE BEAUCHEMIN.
